(57) **CLAIM**

I claim the ornamental design for a palette blank, as shown
and described.

DESCRIPTION

FIG. 1 is a top perspective view of the claimed design after
assembly.

FIG. 2 is a front elevation view thereof.

FIG. 3 is a rear elevation view thereof.

FIG. 4 is a right-side elevation view thereof.

FIG. 5 is a left-side elevation view thereof.

FIG. 6 is a top plan view thereof.

FIG. 7 is a bottom plan view thereof; and,

FIG. 8 is a plan view of a blank of the claimed design before
assembly.

The broken lines in the drawings illustrate features that form
no part of the claimed design.

1 Claim, 6 Drawing Sheets
